[57] **CLAIM**

The ornamental design for a tool for disengaging portions of a lamp socket, as shown and described.

DESCRIPTION

FIG. 1 is a front perspective view of the tool for disengaging portions of a lamp socket showing out new design;

FIG. 2 is a top plan view thereof;

FIG. 3 is a left side elevational view thereof;

FIG. 4 is a right side elevational view thereof;

FIG. 5 is a rear elevational view thereof; and

FIG. 6 is a bottom plan view thereof.

FIG. 7 is a front perspective view of the tool for disengaging portions of a lamp socket showing an alternate embodiment of our new design.

All sides of the design depicted in FIG. 7 are substantially the same as those of the design depicted in FIG. 1 except for the 90° bend of the handle portion thereof.

FIG. 1

FIG. 2

FIG. 3 FIG. 4

FIG. 5

FIG. 6

FIG. 7
